Fig. 3.

Fig. 6.

FIG. 1 is a perspective view of a device for washing applicator heads used in reconditioning car finishes showing our new design;

FIG. 2 is a front elevational view thereof;

FIG. 3 is a rear elevational view thereof;

FIG. 4 is a side elevational view thereof;

FIG. 5 is a top plan view thereof; and

FIG. 6 is a fragmentary, vertical cross-sectional view taken along line 6—6 of FIG. 3.

The pedal is shown fragmentarily in FIG. 5 for convenience of illustration, and it is understood that the pattern of perforations partially shown on the nozzle head in FIG. 5 repeats throughout the indicated area.

We claim:

The ornamental design for a device for washing applicator heads used in reconditioning car finishes, as shown and described.
